J. S. BIRNZWEIG,
DIE FOR BLANKING OUT BUTTONS,
APPLICATION FILED JUNE 26, 1916.

1,229,572.

Patented June 12, 1917.

Inventor
Jacob S. Birnzwieg
By his Attorney
Maurice Block

UNITED STATES PATENT OFFICE.

JACOB S. BIRNZWEIG, OF NEW YORK, N. Y.

DIE FOR BLANKING OUT BUTTONS.

1,229,572.

Specification of Letters Patent. Patented June 12, 1917.

Application filed June 26, 1916. Serial No. 105,841.

To all whom it may concern:

Be it known that I, JACOB S. BIRNZWEIG, a citizen of the United States of America, residing at New York city, Bronx county, 5 and State of New York, have invented certain new and useful Improvements in Dies for Blanking Out Buttons, of which the following is a full, clear, and exact description.

This invention relates to improvements in 10 dies for stamping out blanks for buttons. My improved stamping device is especially arranged to form blanks for buttons having a metal or other back provided with eyes or perforations for the passage of 15 thread. These buttons are blanked out in cup formation, after which metal or other backs are secured to the blanks by means of a forming die (or otherwise) which is not herein illustrated.

20 My improved stamping device is arranged to form the blanks, trim the same, and finally strip the blanks from the male die.

I will not proceed to describe my invention in detail, the essential features of which 25 will be summarized in the appended claims, reference being had to the accompanying drawing, forming part hereof, wherein—

Figure 1 is a vertical sectional view of 30 my improved stamping device;

Fig. 2 is a side elevation of the male die portion of the device, the spring being omitted, and

Fig. 3 is a top plan view of the female portion of the device.

35 As herein illustrated my improved stamping device comprises a male portion A and a female portion B, both of which consist of a plurality of slidably connected members. The female die portion B consists of 40 a support 1 having a counterbore 2 to receive the female die-holder 3, the female die being indicated by 4. The holder 3 is rigidly secured to the support 1 by a set-screw 5, the female die 4 being yieldably 45 supported by a spring 6, a shoulder 7 limiting the upward movement of the die 4. The support 3 also carries a cap 8 having a circular recess 9 and a centrally located opening 10 which surrounds the die 4. The 50 opening 10 will vary in size to suit various size blanks. To form buttons of different thicknesses the blanks therefor, which are flat disks, will be of various diameters, the deeper the blank or cup desired, the greater 55 the diameter of the flat disk out of which the cup is formed; hence, the diameter of

the opening 10 must be proportionate to the size of disk it receives. The cap 8 is removable, so that for a larger or a smaller disk, caps 8 having suitable openings 10 may 60 be substituted. The support 1 will be suitably secured to the bed plate 11 of any suitable press, hand or power.

The male portion A, comprises a support 12 which is carried by or secured to the 65 plunger 13 of the press. The support 12 carries a fixed post 14, which in turn carries the male die 15. The male die 15 is carried by a block 16 set into the post 14. The block 16 carries a shank 17 which passes 70 through the post 14. A nut 18 serves to secure the die in place. It will be obvious that the die 15 is removably secured to the post, and also that the female die is removable from its holder 3. These dies are 75 removable in order that dies for buttons of various designs can be substituted.

The post 14 slidably supports a cutting or trimming device 19 carried by a plate 20. Upon the post 14, and over the cutter 19, I 80 mount a slideable abutment 21 which extends below the edge 22 of the die 15. The abutment 21 is held in place by a pin 23 which passes through a slot 24 therein, and also through a slot 25 in the cutter 19, into the 85 post 14. The abutment 21 is maintained in its lowermost position by a spring 26 located between said abutment and plate 20. The abutment 21 is arranged for an upward movement to expose the blank to the action 90 of the male die and the plate 20 and cutter 19 are arranged for a downward movement to strip the formed blank from the male die, but the abutment and cutter do not have imparted thereto these movements 95 at the same time.

To move the plate 20 downwardly, I slidably mount in the support 12, a plurality of pins 27, which are secured to the plate 20 and extend above the upper surface of the 100 support 12 to strike the stationary head 28 of the press at a certain point during the upward stroke of the plunger 13.

To form a blank, a disk of suitable material (heated celluloid, for instance) will 105 be placed in the pocket 29, formed by the opening 10 in the cap 8, over the female die. When the male die portion A descends, the abutment 21 will strike the cap 8 and come to rest, holding the disk down. A continued 110 downward movement of the plunger will compress the spring 26 and force the male

die through the abutment against the disk over the female die. A still further downward movement compresses the spring 6 and forces the female die downwardly, whereby the blank will be forced into the female die opening 30 in the support 3, which will turn the edge of the blank upwardly and form a cup-shaped element.

When the blank has been forced completely into the die opening 30, its edge, or the edge of the now formed cup, will come into contact with the edge 31 of the cutter 19 and become trimmed.

When the plunger rises the cup shaped blank will be drawn up with the male die and finally into the opening 32 in the abutment 21. When the plunger has moved upwardly far enough, the upper end of the pins 27 will strike the head 28 of the press, whereupon the plate 20 and its cutter will be forced downwardly during the remainder of the upward stroke of the said plunger, and hence force the blank out of the opening 32. Upon the next downward stroke of the plunger, the parts will assume their normal position before the next blank is acted upon.

Having now described my invention, what I claim and desire to secure by Letters Patent is:

1. A stamping device, consisting of a support, a holder removably secured thereto, a movable female die carried by the holder, the holder being provided with a shoulder 35 to limit the upward movement of the female die, yieldable means to oppose the movement of the female die, a removable cap carried by the female die holder having a central opening surrounding the female die, and a male die to coöperate with the female die.

2. A stamping device, consisting of a support, a post carried thereby, a male die removably secured to said post, a vertically 45 movable cutter surrounding the male die, means to operate the male die, and means to operate said cutter at a predetermined point in the operation of the male die, and a female die coöoperating with the male die.

3. A stamping device consisting of a support, a post carried thereby, a male die re-

movably secured to said post, a movable cutter surrounding said male die, a plate secured to said cutter, movable pins to depress said plate to operate said cutter, a spring to return said plate and cutter after the operation thereof, and a female die coöperating with the male die.

4. A stamping device consisting of a support, a post carried thereby, a male die removably secured to said post, a movable cutter surrounding said male die, a plate secured to said cutter, movable pins to depress said plate to operate said cutter, a spring to return said plate and cutter after the operation thereof, a movable abutment, slidably mounted on said post, a spring interposed between said abutment and the plate on said cutter, and a female die to coöperate with said male die.

5. In a stamping device, a support, a male die carried thereby, a movable cutter surrounding the male die, a slidable abutment adjacent the male die and cutter, and a spring tending to force said cutter and abutment in opposite directions.

6. In a stamping device, a support, a male die carried thereby, a movable cutter adjacent the male die, a movable abutment adjacent the male die and cutter, a spring tending to force said cutter and abutment in opposite directions, a female die movably mounted in alinement with the male die, and a spring to oppose the movement of the female die.

7. In a stamping device, a support, a male die carried thereby, a movable cutter adjacent the male die, a movable abutment adjacent the male die and cutter, a spring tending to force said cutter and abutment in opposite directions, a support subjacent the male die, a holder removably secured to said support, a female die slidably supported by said holder, and a spring interposed between the female die and support.

Signed at New York city, N. Y. this 20 day of June, 1916.

JACOB S. BIRNZWEIG.
